[57] CLAIM

The ornamental design for an adapter mount for microphone and the like, as shown and described.

DESCRIPTION

FIG. 1 is an exploded perspective view of an adapter mount for microphones and the like;

FIG. 2 is a side elevation thereof;

FIG. 3 is a top plan view as seen in the direction of line 3—3 of FIG. 2;

FIG. 4 is a bottom plan view as seen in the direction of line 4—4 of FIG. 2;

FIG. 5 is a top plan view as seen in the direction of line 5—5 of FIG. 2; and

FIG. 6 is a bottom plan view as seen in the direction of line 6—6 of FIG. 2.

The side opposite that shown in FIG. 2 is essentially a mirror image thereof.
